CLAIM

The ornamental design for a handguard for an AR type firearm, as shown and described.

DESCRIPTION

FIG. 1 is a first perspective view of a handguard for an AR type firearm according to a first embodiment of the present design;

FIG. 2 is a second rotated perspective view of the design of FIG. 1;

FIG. 3 is a front plan view of the present design of FIG. 1; FIG. 4 is a rear plan view of the present design of FIG. 1; FIG. 5 is a right side view of the present design of FIG. 1; FIG. 6 is a left side view of the present design of FIG. 1; FIG. 7 is top view of the present design of FIG. 1; FIG. 8 is a bottom view of the present design of FIG. 1; FIG. 9 is a first perspective view of a handguard for an AR type firearm according to a second embodiment of the present design;

FIG. 10 is a second rotated perspective view of the design of FIG. 9;

FIG. 11 is a front plan view of the present design of FIG. 9; FIG. 12 is a rear plan view of the present design of FIG. 9; FIG. 13 is a right side view of the present design of FIG. 9; FIG. 14 is a left side view of the present design of FIG. 9; FIG. 15 is top view of the present design of FIG. 9; FIG. 16 is a bottom view of the present design of FIG. 9; FIG. 17 is a first perspective view of a handguard for an AR type firearm according to a third embodiment of the present design;

FIG. 18 is a second rotated perspective view of the design of FIG. 17;

FIG. 19 is a front plan view of the present design of FIG. 17; FIG. 20 is a rear plan view of the present design of FIG. 17; FIG. 21 is a right side view of the present design of FIG. 17; FIG. 22 is a left side view of the present design of FIG. 17; FIG. 23 is top view of the present design of FIG. 17; FIG. 24 is a bottom view of the present design of FIG. 17; FIG. 25 is a first perspective view of a handguard for an AR type firearm according to a fourth embodiment of the present design;

FIG. 26 is a second rotated perspective view of the design of FIG. 25;

FIG. 27 is a front plan view of the present design of FIG. 25; FIG. 28 is a rear plan view of the present design of FIG. 25; FIG. 29 is a right side view of the present design of FIG. 25; FIG. 30 is a left side view of the present design of FIG. 25; FIG. 31 is top view of the present design of FIG. 25;

FIG. 32 is a bottom view of the present design of FIG. 25; FIG. 33 is a first perspective view of a handguard for an AR type firearm according to a fifth embodiment of the present design;

FIG. 34 is a second rotated perspective view of the design of FIG. 33;

FIG. 35 is a front plan view of the present design of FIG. 33; FIG. 36 is a rear plan view of the present design of FIG. 33; FIG. 37 is a right side view of the present design of FIG. 33; FIG. 38 is a left side view of the present design of FIG. 33; FIG. 39 is top view of the present design of FIG. 33; FIG. 40 is a bottom view of the present design of FIG. 33; FIG. 41 is a first perspective view of a handguard for an AR type firearm according to a sixth embodiment of the present design;

FIG. 42 is a second rotated perspective view of the design of FIG. 41;

FIG. 43 is a front plan view of the present design of FIG. 41; FIG. 44 is a rear plan view of the present design of FIG. 41;

FIG. 45 is a right side view of the present design of FIG. 41; FIG. 46 is a left side view of the present design of FIG. 41; FIG. 47 is top view of the present design of FIG. 41; FIG. 48 is a bottom view of the present design of FIG. 41; FIG. 49 is a first perspective view of a handguard for an AR type firearm according to a seventh embodiment of the present design;

FIG. 50 is a second rotated perspective view of the design of FIG. 49;

FIG. 51 is a front plan view of the present design of FIG. 49;

FIG. 52 is a rear plan view of the present design of FIG. 49; FIG. 53 is a right side view of the present design of FIG. 49; FIG. 54 is a left side view of the present design of FIG. 49; FIG. 55 is top view of the present design of FIG. 49; and FIG. 56 is a bottom view of the present design of FIG. 49; FIG. 57 is a first perspective view of a handguard for an AR type firearm according to an eighth embodiment of the present design;

FIG. 58 is a second rotated perspective view of the design of FIG. 57;

FIG. 59 is a front plan view of the present design of FIG. 57; FIG. 60 is a rear plan view of the present design of FIG. 57; FIG. 61 is a right side view of the present design of FIG. 57; FIG. 62 is a left side view of the present design of FIG. 57; FIG. 63 is top view of the present design of FIG. 57; FIG. 64 is a bottom view of the present design of FIG. 57; FIG. 65 is a first perspective view of a handguard for an AR type firearm according to a ninth embodiment of the present design;

FIG. 66 is a second rotated perspective view of the design of FIG. 65;

FIG. 67 is a front plan view of the present design of FIG. 65;

FIG. 68 is a rear plan view of the present design of FIG. 65; FIG. 69 is a right side view of the present design of FIG. 65; FIG. 70 is a left side view of the present design of FIG. 65; FIG. 71 is top view of the present design of FIG. 65; and, FIG. 72 is a bottom view of the present design of FIG. 65.
